(57) **CLAIM**

The ornamental design for a filled pet treat, as shown and described.

DESCRIPTION

Also, U.S. Design application Ser. No. 29/434,859, filed Oct. 17, 2012, entitled Pet Treat Appliance, are each hereby incorporated in their entirety by reference herein.

FIG. 1 is an upper perspective view of a filled pet treat embodying our design;

FIG. 2 is a lower perspective view of the filled pet treat depicted in FIG. 1;

FIG. 3 is a top elevation view of the filled pet treat depicted in FIGS. 1 and 2;

FIG. 4 is a side elevation view of the filled pet treat depicted in FIGS. 1–3, with the opposite side elevation view being identical thereto;

FIG. 5 is a bottom elevation view of the filled pet treat depicted in FIGS. 1–4; and,

FIG. 6 is an end elevation view of the filled pet treat depicted in FIGS. 1–5, with the opposite end elevation view being identical thereto.
